CLAIM

The ornamental design for an infant sock, as shown and described.

DESCRIPTION

FIG. 1 is a right, top, front perspective view of an infant sock showing our new ornamental design; FIG. 2 is a top plan view thereof; FIG. 3 is a bottom plan view thereof; FIG. 4 is back elevational view thereof, with the strap connected; FIG. 5 is a front elevational view thereof; FIG. 6 is a right elevational view thereof; FIG. 7 is a left elevational view thereof; FIG. 8 is a left, top, back perspective view thereof, with the strap connected; FIG. 9 is a right, top, front perspective view thereof, with the strap disconnected; FIG. 10 is a left, bottom, back perspective view thereof with the strap disconnected; FIG. 11 is a right, top, front perspective view thereof, with a sensing device next to the infant sock; FIG. 12 is a right, top, front perspective view thereof, with a sensing device partially inserted into a sleeve within the infant sock; FIG. 13 is a right, top, front perspective view thereof, with a sensing device fully inserted into a sleeve within the infant sock; and,

FIG. 14 is a bottom perspective view thereof, with the sensing device fully inserted into a sleeve within the infant sock.

Objects shown in broken lines are shown for environmental purposes only and form no part of the claimed design.
